UNITED STATES PATENT OFFICE.

JAS. GARDETTE AND HENRY RANCE, OF NEW ORLEANS, LOUISIANA.

APPARATUS FOR FORMING VAPOR FOR MEDICAL PURPOSES.

Specification of Letters Patent No. 26,667, dated January 3, 1860.

To all whom it may concern:

Be it known that we, JAMES GARDETTE and HENRY RANCE, both of New Orleans, in the parish of Orleans and State of Louisiana, 5 have invented a new and useful Machine for Changing Water into Mist for Medicinal Purposes; and we do hereby declare that the following is a full, clear, and exact description thereof, reference being had to the accompanying drawings, forming a part of 10 this specification, in which—

Figure 1 represents a front elevation of the machine. Fig. 2 is a transverse vertical section taken through the red line of Fig. 1.

15 Similar letters of reference indicate corresponding parts in both figures.

Physicians have sought some means of administering medicines to and through the respiratory apparatus, and the only method 20 heretofore imagined has been to employ gases or liquids evaporated for inhalation by the application of heat, so that by boiling the liquid the vapors may be inhaled. This method is very objectionable in many 25 cases and it is very desirable to obtain a means of inhaling any medicine at any determinate degree of temperature, even below the point of evaporation, and even such medicines as cannot be evaporated.

30 Our invention consists in the employment of a rotary wheel with hollow radial arms terminating in very small orifices, through which the liquid is thrown in jets by centrifugal action, and it further consists in arranging on the ends of independent radial arms, which are attached to a solid hub rotating in an opposite direction to the first wheel deflecting plates, against which the 35 jet of liquid is thrown which serve the purpose of dispensing and diffusing the particles of liquid throughout an apartment so that they can be taken into the respiratory apparatus without inconvenience, as herein-after fully described.

40 A A' represent two standards fixed to a base, B, and upon these standards are supported the following devices: D is a reservoir for containing the medicinal compounds, which are to be vaporized or mistified, and E is a tube communicating with the bottom of said reservoir, and furnished with a stop-cock, F. This tube is bent at right angles, and the angle secured to the top of the standard, A', by suitable bolts as

55 shown at G, Fig. 2. The bent portion, E', proceeds out about midway between the standards, A A', and serves as the axial support for the tube, H, of the radial arms, J. These arms, J, are all made hollow, as clearly shown by Fig. 2, of the drawings, 60 and terminate in very small orifices, a a, through which the liquid which flows from the reservoir, is discharged in fine jets as the arms are swiftly rotated.

K is a solid shaft bolted to the center of 65 the hub, H, and supported in a journal box upon top of the standard, A, and passes out from the standard a suitable distance and receives a belt pulley, b. This shaft, K, 70 passes through a hollow shaft, L, which has a hub, M, on its inner end, and a pulley, c, similar to that lettered b, on its other end. From the hub, M, of this hollow shaft, L, proceed radial arms, N, numbering as many 75 as there are hollow arms, J, and on the end of each arm, N, are fixed, at right angles to the arms, deflecting plates, P, of a quadrangular shape, and secured to the ends of the arms, N, at any desirable angle found best adapted to the purpose of separating 80 the particles of liquid as it rises from the ends of the arms, J, and throwing off the fine particles which are held in suspension in the air in the apartment where the apparatus is to be used.

85 The arms, J and N, are rotated in opposite directions to each other by means of the belts, e f, which pass over the pulleys, b and c, and over the two-belt wheel, R, the belt, f, 90 being crossed, as represented by Fig. 1, and the whole machine operated by means of the handle, S.

Liquid being poured into the reservoir, D, and the cock, F, opened it flows down the tube, E, and through tube, E', and fills the 95 arms, J. The parts are then rotated very swiftly, and the centrifugal action discharges the liquid through the orifices, a, of the arms, J, and as it is thrown off it is struck by the plates, P, and flies off in the 100 form of fine mist, which soon charges the air of the entire apartment.

In the use of this apparatus what may be considered very material and highly important is, that no decomposition of the ingredients takes place, as undoubtedly must arise when heat is applied to vaporize the compounds.

What we claim as our invention, and desire to secure by Letters Patent, is:—

The reduction of liquids into mist or vapor, at any degree of temperature, without evaporation by means of a centrifugal pump, or its equivalent, projecting fine jets of the liquid against disks set at any angle,

substantially as described so that the liquid may be respired with the atmosphere.

JAMES GARDETTE.
H. RANCE.
